CLAIM

The ornamental design for a ferris wheel greeting card, as shown and described.

DESCRIPTION

FIG. 1 is a perspective view of the ferris wheel greeting card of the present invention, in an open position.

FIG. 2 is a front view of the ferris wheel greeting card of FIG. 1.

FIG. 3 is a rear view of the ferris wheel greeting card of FIG. 1.

FIG. 4 is a left side view of the ferris wheel greeting card of FIG. 1.

FIG. 5 is a right side view of the ferris wheel greeting card of FIG. 1.

FIG. 6 is a top down view of the ferris wheel greeting card of FIG. 1.

FIG. 7 is a bottom up view of the ferris wheel greeting card of FIG. 1; and,

FIG. 8 is a perspective view of the ferris wheel greeting card of FIG. 1, in a closed position.

The broken line showing of portions of the ferris wheel greeting card is included for the purpose of illustrating environmental structure and forms no part of the claimed design.

1 Claim, 7 Drawing Sheets(56)
